DESIGN FOR A CARPET SWEEPER

Irving Richardson, Newark, N. J.

Application August 6, 1938, Serial No. 79,171

Term of patent 7 years

To all whom it may concern:

Be it known that I, Irving Richardson, a citizen of the United States, residing in the city of Newark, county of Essex and State of New Jersey, have invented a new, original, and ornamental Design for a Carpet Sweeper, of which the following is a specification, reference being had to the accompanying drawing, forming part thereof.

Fig. 1 is a perspective view of a carpet sweeper showing my new design, the handle being conventional and shown fragmentarily for convenience of illustration;

Fig. 2 is an end elevational view of the shell member only; and

Fig. 3 is a front elevational view of the disclosure in Fig. 2.

I claim:

The ornamental design for a carpet sweeper, as shown and described.

IRVING RICHARDSON.
